DOG'S FEEDING BOWL

Ruth S. Frazin, Yonkers, N. Y.

Application July 21, 1954, Serial No. 31,530

Term of patent 7 years

(Cl. D12—2)

The figure is a perspective view of a dog's feeding bowl, showing my new design.

The appearance of the undisclosed side of the dog's feeding bowl is the same as the side shown.

I claim:

The ornamental design for a dog's feeding bowl, substantially as shown and described.
